UNITED STATES PATENT OFFICE.

WILLARD O. LATHROP, OF CINCINNATI, OHIO.

SINGLE-CONE SPIRAL-SPRING BED OR SEAT STRUCTURE.

1,186,320.

Specification of Letters Patent.

Patented June 6, 1916.

Application filed February 21, 1913. Serial No. 749,842.

To all whom it may concern:

Be it known that I, WILLARD O. LATHROP, a citizen of the United States of America, and a resident of Cincinnati, in the county of Hamilton and State of Ohio, have invented a certain new and useful Improvement in Single-Cone Spiral-Spring Bed or Seat Structures, of which the following is a specification.

10 This invention relates to spring-bed structures in which an inverted-cone spiral-spring is supported and fastened at its lower narrowest extremity upon intersecting tie-wires, and its object is to provide a hook-shape loop or bend in the lowermost volute or coil-extremity of an inverted-cone spiral-spring whose end is sloped downwardly and is adapted to snugly engage in one of the corners of cross tie-wire intersections, 15 the latter being composed of a centrally-bent arched portion in one of the tie-wires and a centrally-bent depressed portion in the other tie-wire, the said centrally-bent portions crossing each other at that point 20 in each and the lower volute of the spring, beginning with said hook-shape extremity, being adapted to wind or pass under the said depressed portion of one tie-wire, thence over the said arched portion of the other 25 tie-wire to one side of its central bend, thence again under the first-named tie-wire slightly beyond the depressed portion thereof and thence rising upward away 30 from the body portion of the said second-named tie-wire and developing in diameter to form the inverted-cone spiral-spring that the mattress of a bed or of the upholstered portion of a seat rests upon. The peculiar manner of interlocking 35 the lower hook-extremity of the inverted-cone spiral-spring with the intersecting arched and depressed portions of the cross tie-wires forms the essential feature of the invention herein and is at once an extremely simple, firm and durable device, 40 easily made and kept in repair, as well as replaced when desired.

In the accompanying sheet of drawings, Figure 1 is a fragmentary plan view showing one corner of a spring-structure that brings clearly to view the attaching and supporting essential elements of my invention herein, the spring being shown broken off not far from its lower attaching-end; Fig. 50 2, a fragmentary elevation showing a part of the inverted-cone spiral-spring, one of

the cross tie-wires, the border or binding wire, and a cross-section of the other cross tie-wire together with the lower hook end or extremity of the spring, showing the interlocking feature, and taken on the dotted-line *a*, *a*, of Fig. 1; Fig. 3, a transverse section taken at right-angles to that seen in Fig. 2 and on the dotted-line *b*, *b*, of Fig. 1; and Fig. 4, an elevation of an inverted-cone spiral-spring showing it supported between upper and lower cross tie-wire structures and embodying my invention herein. This view is added more in the nature of making clear the peculiar class of spring to which my invention is especially applicable.

1 indicates the border or binding wire of the lower or supporting portion of the spring-structure, 2 being each one of the usual parallel cross tie-wires extending in one direction from their hook-ends 3 along the border-wire 1, and 4 being each one of the usual parallel tie-wires that cross the tie-wires 2 at suitable intervals apart and are hooked to said border-wire at 5. 80

The border-wire 1 is a heavy one, as customary, and the cross tie-wires 2 and 4 are lighter ones, both of the same gage.

At crossings or intersections of the tie-wires 2 and 4, each tie-wire 2 is depressed 85 or bent downward at 6 and each tie-wire 4 is arched or bent upward as shown at 7, the arch taking a definite central bend to provide a definite seat for the central portion of the depressed bend 6 in the tie-wire 90 2, as best seen in Fig. 3. The said definite central bend in the arch 7 prevents any lateral shifting of the tie-wires at the crossings or intersections and forms a secure interlock. The depressed portion 6 and the arch portion 95 7 have straight sloping side-members whereby suitable corners or angles are provided that assure ample seating capacity for the lower attaching-end of the spring that is in approximately axial-alinement with the 100 volutes of the spring.

8 indicates an inverted-cone spiral spring whose broad upper end 9 is duly attached to the upper wire-structure 10 of the bed or seat bottom, as best seen in Fig. 4 and whose lower narrow volute 11 is formed into a hook that is downwardly sloped or turned at a slight angle from the horizontal at its extremity, as best shown at 12 in Fig. 3.

In attaching the lower end of the spring 110 in position on the supporting-intersection composed of the cross tie-wires 2 and 4, the

angularly sloped or depressed extremity 12 snugly seats or rests in a corner formed by said cross tie-wires 2 and 4 and with its end in abutting-engagement with the depressed portion 6 of the tie-wire 2, as best seen in Fig. 3, and dotted in Fig. 2, and thence the narrow volute 11 passes over and in contact with the tie-wire 4 so as to seat at the beginning of the arched portion 7, thence the wire 10 of the spring passes under the intersecting tie-wire 2 so as to contact with the beginning of the depressed V-shape portion 6 thereof, thence said wire of the spring advances over and in contact with the said tie-wire 4 at the other end of the arched portion 7, thence said spring wire advances under the cross tie-wire 2, in contact therewith but beyond the depressed portion 6 thereof, thence over the said cross tie-wire 4 but not in contact therewith as the spring has then begun to ascend or rise in its convolutions toward the broad upper end 9 thereof.

It is obvious that the contact of the angularly sloped or depressed end or extremity 12 and of the succeeding parts of the lower volute of the spring wire in connection with the arched portion 7 and the depressed portion 6 of the intersection of cross tie-wires 2 and 4 will make a firm and substantial interlock that will not become loose or detached in use. This fastening can be readily effected and the spring can be readily removed when desired by simply disengaging the angularly sloped or depressed end or extremity 12 from its resting corner.

I prefer to make the wire spring of the same gage as that of the cross-ties 2 and 4, whereby the best form of interlock results, although the spring itself might be of heavier wire to suit the greater weights that may be imposed upon it in use.

I claim:—

A single-cone, spiral-spring bed or seat structure comprising a vertical, conical spiral-spring that tapers upwardly and with its broadest portion thereby disposed upwardly and having at its lower end a U-shape or hook formation whose straight extremity slopes downwardly, a transverse horizontal tie-wire having an inverted-V-shape or angularly-arched portion provided therein and adapted to engage the said lower, straight sloping extremity of the spring, and another tie-wire lying at right-angles to the first-named tie-wire and having a V-shape portion therein that is in crossing-contact with the said inverted-V-shape angularly-arched portion of said first-named tie-wire and is thereby adapted to interlock with and securely stop the lower hook-shape extremity of the spring at the crossing-point of the said tie-wires that axially-aligns the spring and with the said straight sloping end of said U-shape extremity abutting the said V-shape portion of the second-named tie-wire.

WILLARD O. LATHROP.
